UNITED STATES PATENT OFFICE.

CARL W. WEBER, OF OAKLAND, KANSAS.

DESIGN FOR A LIGHT REFLECTOR.

Application filed June 10, 1921. Serial No. 476,559. Term of patent 14 years.

To all whom it may concern:

Be it known that I, CARL W. WEBER, a citizen of the United States, residing at Oakland, in the county of Shawnee, State of Kansas, have invented a new, original, and ornamental Design for Light Reflectors, of which the following is a specification, reference being had to the accompanying drawings, forming a part hereof.

In the drawings—

Fig. 1 is a top plan view of my ornamental design:

Fig. 2 is a side view.

I claim:

The ornamental design for a light reflector, as shown.

CARL W. WEBER.
